ATTORNEY

UNITED STATES PATENT OFFICE.

JOHN A. BURR, OF NEW YORK, N. Y.

SHUTTER-FASTENER.

SPECIFICATION forming part of Letters Patent No. 363,207, dated May 17, 1887.

Application filed July 29, 1886. Serial No. 200,386. (No model.)

To all whom it may concern:

Be it known that I, JOHN A. BURR, of the city, county, and State of New York, have invented a certain new and useful Improvement 5 in Shutter-Fasteners, of which I declare the following to be a full, clear, and exact specification, reference being had to the accompanying drawings, forming a part thereof.

This invention is in the nature of an improvement in the shutter-fastener heretofore patented by me May 19, 1885, in a patent numbered 318,414; and the invention consists of the guard and springs constructed and combined in the manner hereinafter particularly described, shown, and claimed.

In the accompanying sheet of drawings, Figure 1 is a front elevation of my improvement; Fig. 2, a section of same taken in the line *x x*, Fig. 1; and Fig. 3, a vertical section 20 in the line *y y*, Fig. 2.

Similar letters of reference indicate like parts in the several figures.

As is stated above, this invention is simply an improvement on the shutter-fastener patented by me May 19, 1885. In the device so patented the pivoted hasp or catch A of the shutter B passed through the outside of the shutter and terminated in a plate, C, against which a stream from the nozzle of a hose-pipe could be directed with force enough to disengage the catch from its retaining-bar D, and so, in case of fire, afford ready means for opening the iron shutters of a warehouse and enable the firemen to play through the window to the fire within the building; but it was found in practice that while the stream from a hose-pipe would readily open the shutters, as stated, so also would a stick or a well-directed stone in the hands of designing persons; and it is to remedy this defect that I now fix to the shutter B, on its outer surface and immediately below the plate C of the catch A, a guard, E, of any convenient shape, but necessarily perforated, or of gridiron form, as is shown in Fig. 2, so that, although a guard is interposed between the plate C and the impact

of a stone or stick, still the stream from the hose can readily pass through the interstices in the guard and impinge against the plate, and so open the catch with the same facility 50 as if the guard were not present. Now, the disengagement of the catch in the manner described is of course essential to the opening of the iron shutters, but the shutters will not because of this disengagement fly open to admit the stream from the engine unless some means be provided for that purpose.

In my patent before referred to I described springs fixed to the lower part of the window-frame; but a still better means for opening the 60 shutters consists in providing each shutter at or near its top with a bracket, F, to which, in any desirable manner, is fixed one end of a spring, *a*, the other end of the spring being secured to the wall of the building, so that the 65 spring is in a state of tension or torsional strain when the shutters are closed and held by the catch A; but when the catch is disengaged this spring is free to exert its elastic force, and does exert it, in throwing the shutter open and holding it back against the wall, which could not be done by the springs described in my previous patent. These springs *a*, by their action in holding the shutters back against the wall of the building, render unnecessary the ordinary turn-buckle commonly used for that purpose.

Having now described my invention, what I claim as new, and desire to secure by Letters Patent, is—

In combination, the following elements: a shutter, B, a pivoted catch, A, passing through the shutter and provided at its outer end with a plate, C, a retaining-bar, D, or similar device, to engage with said catch, and a perforated 85 guard, E, fixed to the shutter B below and as a protection for the plate C, as and for the purpose described.

JOHN A. BURR.

In presence of—

WM. P. BURR,
RUFUS P. LIVERMORE.
